SUSPENDERS

Filed Jan. 21, 1931

2 Sheets-Sheet 1

UNITED STATES PATENT OFFICE

CARL G. ARNOLD, OF LOS ANGELES, CALIFORNIA

SUSPENDERS

Application filed January 21, 1931. Serial No. 510,173.

The invention relates to improvements in garment supporting suspenders, adapted to support a plurality of garments, and having shoulder pieces with step adjusting devices, and suspender tabs to be step adjusted.

In particular, the invention is an improvement in suspenders of the application 415,978 filed December 23, 1929, by same above named Carl G. Arnold; and improvement is made in the straps, the strap connection at the rear, the suspender ends, the hookloops and the connecting strip.

The objects of the improvement are to present novel structures of such parts, as hereinafter described and claimed, and illustrated on the accompanying two sheets of drawings. Hereon Fig. 1 is a complete view of the suspenders, and showing modifications. Figs. 2 and 3 are details of the pad which connects the shoulder pieces at the rear. Figs. 4 and 5 are front and side views of one hookloop in Fig. 1, and Fig. 6 also is a side view thereof with a piece of shoulder strap in lengthwise section. Figs. 7 and 8 are front and side views of a modified hookloop in Fig. 1, and Fig. 9 is a top view of the loop on slanting section line $s-l$ in Fig. 7. Figs. 10 and 11 are front and side views of another modified hookloop, and Fig. 12 is a top view of the loop on section line $s-l$ in Fig. 10. Figs. 13 and 14 are front and side views of another modified hookloop, and Fig. 15 is a top view of the loop on section line $s-l$ in Fig. 13. Fig. 16 illustrates and sketches a connecting strip in Fig. 1, applied to the hookloops in three different modified ways. Fig. 17 is a detail front, and a side, view of a safety pin, shown in Fig. 1. Fig. 18 is a top view of the rear garment buttons in Fig. 1; and Fig. 19 is a side view thereof on section line $s-l$ in Fig. 18.

Fig. 1 shows two similar shoulder pieces with front portions 1, 2; rear portions 3, 4; and rear parts or rear suspender tabs 5, 6. The parts 1, 3 and 2, 4 are shoulder straps specifically, passing over the shoulders of a person at 7, 8. The shoulder straps may be made of proper material as, leather, or webbing. The straps from end to end have in each of them formed a continuous series of

longitudinal slits or openings 9, each about one quarter inch long, or longer if appropriate, and suitably spaced apart for desirable step adjustment, as will be set forth later on. When the straps are made of webbing, the 55 slits are preferably woven into the straps, that is directly made or left while the webbing is being woven; this provides a simple and advantageous way for forming the slits.

The rear end parts or rear suspender tabs 60 5, 6 being of lesser width than the shoulder straps, may be made of similar material as the shoulder straps, and from end to end also have a continuous row or series of longitudinal slits 11 about three quarters of an inch 65 long each, and properly spaced apart, as desirable, adapted to serve as step by step adjusted button holes, as will be brought out later on.

It is noted here that on the drawings the 70 slits 9 and 11 are not always illustrated as all of them running continuously from end to end in each part or section, but are omitted at some places, in order to keep the drawings clearer there. However the presence of such 75 omitted slits will be apprehended inferentially from the arrangement of other slits illustrated and similarly located. The shoulder straps together with the rear tabs 5, 6 have previously been designated as shoulder pieces. 80 In these, the slits 9 and 11 may be considered or viewed as running as one continuous row from end to end of the pieces, that is, in each piece running from the free end of the rear tab to the free front end of part 1, or 2; especially so, if longitudinal slits 9 and 11 are made of same length. The slits 9 and 11 are simply indicated by a single stroke, because, particularly in woven in slits, there is no distinct opening seen. But when such slits are 85 expanded by the insertion of a hook or of a button, as described later, take the shape somewhat like buttonholes.

The purpose and advantage of having continuously running slits will appear later. 95

The parts 3, 4, 5, 6 are united at the rear of the suspenders to form a pad 18, in a manner detailed in Figs. 2 and 3. In Fig. 2 the end of portion 4 is put down at an angle of about thirty degrees against the vertical middle or 100

- center line of the suspenders; then upper end of tab 5 is placed on 4, forming an angle of about twenty-two degrees with the center line; then upper end of tab 6 is put on 5 and 4 in such a way, that 5 and 6 crossing each other, symmetrically to the center line, form an angle between them of about forty-four degrees in descending downward; see also Fig. 1.
- 10 Then in Fig. 3 end of portion 3 is placed on top of 6, 5, 4 symmetrically with 4, whereby 3 and 4 cross each other and form an angle of about sixty degrees between them ascending upward; see also Fig. 1.
- 15 The parts 3, 4, 5, 6 are hereupon integrally united by stitching them together to form pad 18, Fig. 1. In Fig. 3 the union is done by cross stitching together 3 and 5 twice at 13, and 4 and 6 at 14; then lengthwise stitching 15 and 16 are made, crossing each other at 17. By this kind of stitching the parts 3, 4 and 5, 6, particularly if 3, 4 are of elastic webbing, when swung sidewise by the movement of the body, and are stretched, in a way move 20 pivotally on 17. Thereby an integral yet somewhat yielding pad 18 is formed, better distributing the strains in 3, 4. At pad 18, four pieces come together, the two straps and the two tabs. This device permits the tabs 25 to converge under a lesser angle, than the angle formed by the straps; further, as the tabs are of lesser width than the straps; and their crossing lies between the straps, a simple, compact, yet yielding pad, that also is 30 adjusted to the garment buttons, is produced. A still further adjustment of the pad in connection with the tabs 5, 6 is set forth later on.
- The front portion of the shoulder piece or strap part 1 shows a hookloop 19, detailed in 35 Figs. 4, 5, 6; it is preferably made of a single piece of noncorrosive metallic wire. Hookloop 19 consists of a stem 20 having at its one, upper, end a hook formed by a bar 21 and tongue 22; tongue 22 is bent and ends in a pin 40 23 which is directed at a substantially right angle to the plane in which hook 21, 22 lies, and is directed outward, that is, away from the center line of the suspenders. To the other, lower, end of stem 20 are joined a 45 branch 24 and a base 25; by bending, from 25 back toward the branch 24, in the plane constituted by 24, 25, the branch 26 is shaped, extending up to 24, whereby a closed loop 27 is produced. The loop 27 and the hook 21, 22 lie in planes at right angles toward each 50 other. The hook bend, or top, 28 in Figs. 1 and 6, is seen passed through 9', that is, one of the slits 9. When 21, 22, with hook top 28, is placed into a slit 9, in a manner next to be 55 described, the slit 9 widens out assuming a sort of button hole shape 9'.
- 60 Hookloop 19 is engaged with any slit 9 in the following manner: 19 in position shown in Fig. 4 is turned ninety degrees into position 65 as shown by Fig. 5, with pin 23 extending out-

ward, that is, away from the body of a wearer. Then pin 23 is placed, in Fig. 1, inside of strap 1, at right angle thereto, inserted into 9', that is 9 widened, and pushed forward up to 22. Hereupon hook 21, 22 is turned ninety degrees, back again into a position as shown by Fig. 4; 23 will then be lying flat outside on 1. Hereupon hook 21, 22, by seizing loop 27 is pulled downward till 28 rests in slit or buttonhole 9' and 19 assumes the position in 70 Figs. 1 and 6. To disengage 19 from a slit the reverse manipulation is carried out. Thus 19 can be step adjusted into any desired slit 9.

Pin 23 prevents tongue 22 from slipping out, by itself, except when manipulated, when strap 1, 3 is thrown off the shoulder at 7 and left hanging loose, as will yet be mentioned later on. Therefore pin 23, being used for insertion into 9', and by securing the hookloop 19 from falling out of 9', is called an inserting and securing pin. But pin 23 has yet the function of a retaining pin, as will be set forth hereafter.

Hookloop 19 with 28 as universal pivot will 90 freely swing on 9' sideways, forward and backward, following up the motions of the shoulder strap and a garment connected to the hookloop by the suspender tab, to be described next. Also the loop 27 through pivot 95 28 yields readily, when the shoulder strap is thrown off the shoulder, as will be referred to later.

On base 25 of 19, Fig. 1, is placed a one piece front suspender tab 29 doubled or looped at 29', which alike to tabs 5, 6 is of similar material, and from end to end has similar continuously running slits 30, adapted to serve as buttonholes, and also suitably spaced apart for step adjusting use. Tab 29 100 is adapted to slide on 25 when loop 27 swings pivotally, or when 29 itself moves in connection with the attached garments.

Line 32, dotted, represents the upper edge 110 part of, an outer garment, as pants, and line 33, an inner garment, as drawers. To 32 are inside fixed buttons 34, 35, dotted, and to 33 buttons 36, 37, inside or outside. The slits 30 of 29 serving as buttonholes at 38, 39, 40, 41 are shown engaged with buttons 34, 35, 36, 37. 115 Buttons or slits 42, 43 are below 40, 41 and are shown not engaged; but 40, 41, 42, 43 could be buttoned on 34, 35, 36, 37 whereby the folded or doubled tab 29 would be 120 lengthened, that is lowered, in height, with lowered 32. Similarly, by placing buttonholes 44, 45, 38, 39 over buttons 34, 35, 36, 37, tab 29 could be shortened, or 32 raised. This is a sort of step adjustment, and in connection with step adjustment of slits 9 could be 125 used to exchange wearing out slits or buttonholes 9, 30 for sound ones. As obvious, 29 is placed into or out of closed loop 27 by passing an unbuttoned free end of 29 into or out of 27.

In Figs. 1, 7, 8, 9 a modified hookloop 46 is drawn; it is similar to 19, but there is a differently constructed loop 47. From branch 24 and base 25 is bent back a free branch 48 which runs toward 24, but sideways out of plane 24, 25, past 24, here leaving an opening or passage 49; then tip 50 is bent around 24, so as to continue opening 49 for passing suspender tab 51 into loop 47. This 10 loop is an open loop as distinguished from closed loop 27.

Tab 51, Fig. 1, when attached to the garment buttons, as described below, can, in the folded or doubled form shown, be placed 15 through passage 49, in and out of loop 47, in the way now to be set forth. It will be seen, that on the drawings, Fig. 1, strap 2 is broken off below 9' down to where the short piece of 2 is left, for clearer illustration.

20 First, in the same manner as described for hookloop 19, the hook 21, 22 of 46 is put into a slit 9' of strap 2. Then tab 51 and hookloop 46 are manipulated for engagement in this way: Tab 51 is buttoned to garments 32, 33, 25 to be described more in detail. The hook of hookloop 46 having been placed into 9' before connection of 51 with loop 47, the hookloop 46 is swung ninety degrees around its pivot 28 toward the inside into the horizontal position 30 shown in dotted lines; then the folded or doubled part 51' in the shape of an inverted U is lifted over dotted loop 47 and made to straddle on dotted stem 20. Now swinging 46 back from the dotted position into the 35 previous full line position, 51 slides along branch 24 through passage 49 to base 25 and assumes the location in Fig. 1, being connected with loop 47 and adapted to slide on base 25. By reverse manipulation 51 can be 40 detached from 47.

Through the construction of free branch 48 with tip 50, tab 51 is prevented from sliding out, by itself, from loop 47, if the shoulder strap 2, 4 is thrown off at 8 sideways and 45 hangs down, as will be referred to later, except when manipulated. In this feature, loop 47 functions like a closed loop 27; however 51 by unbuttoning one end may also be passed into 47, as tab 29 is passed into 27.

50 The one piece front tab 51, same in material and structure as is 29, is shown in a modified manner applied to garments 32, 33. There are two buttons 53, 54 on 32, but only one button 55 on 33, which engage buttonholes 56, 57, 58 and carry 32, 33. One button 55 may be sufficient and by pulling the garment 55 with button 55 a little sideways, 55 could be made to engage buttonhole 60, if this appears desirable.

60 By the sliding motion near 51' the suspender tab 51 will wear there; to lengthen the life or use of 51, the weakened place can be shifted by putting buttonholes 59, 58, 62 on buttons 55, 53, 54 or in some other way by 65 making use also of buttonholes 60, 61 in a

suitable manner. Or, tab 51 may entirely be taken off the buttons, taken out of the loop and entirely reversed, then again inserted into the loop, so that the former underside becomes the upper side; then any suitable buttons and buttonholes may be selected to obtain a new place that is sound for wear. Thus tab 51 is reversible, and is variable as to the use of its variable buttonholes.

Further, tab 51 through its buttonholes can be regulated in height similarly as described for tab 29. It is also evident that tab 29 can be used reversible, and variable in its button holes, for the purposes as set forth for tab 51.

It will be understood that in the symmetrical arrangement of suspenders and their shoulder straps, as is usual, the tabs in the form 29 and the buttons as applied there will be used alike on both sides of the suspenders, or the tabs 51 used in their form and button arrangements for supporting a plurality of garments.

Figs. 10, 11, 12 represent a modified form 90 of hookloop, similar in structure and operation to hookloop 46 with the difference that tip 50 in 46 is left off, and there remaining only a short passage 49'. If in this form the branch 48 were bent over to touch, and lie on, 24, leaving no passage, a closed loop 95 would be formed similar to loop 27.

Figs. 13, 14, 15 present a modified form of the hookloop of Figs. 10, 11, 12, in so far, as branch 48 of Fig. 10, does not extend up to 24 in Figs. 13 and 15, but stops short of 24, 100 forming a shorter branch 48' and leaving an opening or passage 49".

It is obvious, that the two modified hookloops just described can be used in place of hookloops 19 or 46 on each side of the suspenders, symmetrically.

Instead of the loops of the hookloops lying inside the straps, as previously described, the loops could be arranged to lie outside on the straps, and the pins 23 on the inside properly located, so that the connecting strip 73, to be described farther on, may properly connect the hookloops. This, in one way, could be done by exchanging hookloops 19 and 46 in Fig. 1, that is, inserting 23 of 19 into 9' of strap 2 on the outside of 2, and pin 23 of 46 into 9', outside of strap 1.

Or, the same position of pins 23 inside, may be obtained by simply, in Fig. 1, putting the right shoulder strap to the left, and the left to the right; hereby the straps together with pad 18 will, for use, become turned over and reversed.

In Fig. 1, and with the tabs 5, 6 omitted in Fig. 18 and Fig. 19, for clearness' sake, the buttons 63, 64, 65, 66 and 71 are shown as located on the rear of the garments 32 and 33. On garment 32, preferably on the inside, are fixed the two pairs of buttons 63, 64 and 65, 66 engaged by the button holes 67, 68 and 69.

69, 70. By using the two pairs of buttons, 32 is better and safer supported at the rear; should one of these buttons get loose, the other adjoining button will yet support 32. 5 But, if desired, only the usual one pair of buttons at the rear of pants, here 32, as made and sold, may be used in place of the four buttons.

By proper choice and engagement of opposite slits or buttonholes 11 with the rear buttons, the rear tabs 5, 6 can be step adjustingly lengthened or shortened in height, similar as described for the front tab 29. Thereby pad 18 may be adjusted to the best position 15 on the back of the wearer.

On the rear no buttons are necessary to uphold the inner garment 33, as drawers, as the buttons at the front of 33, are sufficient to hold 33, and can be conveniently handled.

20 However, if desired, 33 may have a rear button 71, preferably fixed to the outside of 33, for suitably aligning with inside buttons 63 and 65, Fig. 19. Hence the buttonhole 72 in tab 5, may properly engage button 71. 25 When button 71 is thus made use of, the tabs 5, 6 support two, or a plurality of, garments at the rear.

The drawings illustrate the support of two garments 32, 33 by the suspenders. It is easily comprehended, that a third garment, like overalls, placed outside over the pants, with properly located buttons, can still in addition be attached to the tabs. It would involve a mere carrying forward of the ideas and 35 arrangements previously set forth.

As previously described, the garment 33, as drawers, has buttons fixed to 33 at the front and these buttons are held in the buttonholes of the front tabs.

40 Usually drawers, as presently made and sold, have strips sewed onto the waistband in place of buttons just mentioned. The strips function as suspending loops, when one end of the suspender tabs by unbuttoning and 45 buttoning is placed under the strip.

It is evident that the front tabs described in this specification may also thus be applied to drawers having strips serving as suspending loops.

50 In Fig. 1, 79 is a connecting strip of similar material as the tabs 29, 51 and also has a continuous row of slits 74 suitably spaced apart for step adjustment. In Fig. 16 the strip 73 is shown in detail connecting the 55 tongues of hookloops 19 and 46. One slit 74' is slipped on pin 23, or pin 23 inserted into slit 74', and slid up to tongue 22, where it is held at the corner formed by 22 and 23, or in this corner, when the hookloop 19 by the 60 pull of the strip slants inward. Similarly a suitable slit 74'' is placed on tongue 22 of the hookloop 46. In this manner the shoulder straps 1, 2 are held in safe position and their distance is regulated.

65 The two pins 23 prevent the strip from

falling off and therefore act as retaining pins, beside their previously described functions as inserting and securing pins. To disconnect strip 73, only one end need be slipped from one tongue 22, and the other end may remain connected with the other tongue 22. 70

In Fig. 16 connecting strip 73', in dotted lines, sketches the modified connection of loop 27 with tongue 22 of 46, which latter connection is similar to that of strip 73 at 74''; and, as it will be readily understood, is not illustrated to keep the drawings clear.

Since loop 27 is closed, to insert strip 73', the branch 26 is bent sideways open and a slit of 73' is slipped upon 26, then 26 is 80 bent back and 73 is thus steadily held in 27.

As is obvious, some modified form of hook-loop with an open loop may take the place of 19. As loop 27 lies inside strap 1, that is, 85 between the strap and the body of the wearer, that end of 73' will also lie inside the strap. But the other end on tongue 22 of 46 will lie outside, and therefore may be handled with greater facility; this is an advantage 90 with strip 73'. The dotted strip 73'' is applied to the two hookloops 47 and 27; at 27 the connection would be same as for 73', but is not illustrated, same as in case of strip 73' at 74''. At the other end, 73'' is slipped with 95 one of its slits over tip 50 and is then drawn up to 48.

Unless a safer connection is desired between straps 1 and 2, strip 73 could be omitted. However 73 performs an additional useful function. A safety pin shown in Fig. 1 and in detail in Fig. 17, is inserted into a slit 74 in about the middle of 73. This safety pin consists of a wire 75, Fig. 17, bent over at the lower end to form a pointed spring pin and at the upper end bent over and formed at its end to have a flattened pin rest for the point of the spring pin. In use, the pointed pin is passed through the end of a necktie, indicated by dots 76, and the safety pin assumes the position Fig. 17, in side view, holding the necktie in place. 100

But even without using a safety pin, strip 73 may hold a shirt and necktie better in place when located over them.

105 The suspenders may, in one mode, be operated as follows. The rear tabs 5, 6 are fastened to the buttons there, to choice, and adjusted in such a way that pad 18 is conveniently located, as described before. Then the front tabs, in any desired manner, are attached to the garment buttons of 32, 33; then these tabs are passed into the loops on both sides of a chosen form of hookloops, and these hooks inserted into suitable, step adjusting slits 9. Then the connecting strip 110 73 is adjustingly applied.

115 By the reverse way the front suspender straps may be removed. But this can also be done by only throwing the shoulder straps off the shoulders, after disconnecting the con- 115

necting strip at one of its ends, and the buttons on garment 33 when necessary, the hanging down shoulder straps can be lifted back again. As the loops swing freely, and the tabs slide therein, great flexibility and ready yielding is attained for putting the straps off and on, especially so, if the straps are of elastic webbing.

Following advantages of the improved 10 suspenders are cited.

A plurality of garments is carried in a varied, simple and efficient manner. The operation of the suspenders and their adjustments are readily effected. There are 15 few parts, easily manufactured and assembled. Only the simple hookloops in various forms, bent from noncorrosive wire, are of metal.

The shoulder straps, suspender tabs and 20 connecting strip when, preferably, made of webbing, have the slits therein woven in, in a simple inexpensive manner. The straps, tabs, strips may simply be cut off from a roll at any place, and then are ready for 25 assembling. Further, the shoulder straps, or shoulder pieces, are reversible.

The tabs being reversible, and variable in 30 their buttonhole slits, last longer, as wear can be taken up; moreover the tabs and strips may easily be replaced by new ones. They could 35 be sold by the yard, and the user may cut them to proper length. By the shifting of wearing out slits, the straps will also last longer.

35 The rear pad is designed to provide a good adjustment and is easily made. The connecting strip is readily handled, holds the 40 suspenders safely, and also holds a necktie in position.

40 The suspenders have great flexibility, easily following the motions of the body and garments, and favoring a ready throwing off of the shoulder straps sideways without unbuttoning.

45 An incidental advantage is that the upper slits in the front tabs, where not serving as buttonholes, may be used for holding some article, as, for instance, the key ring or hook of a bunch of keys, or the end cross 50 bar of a watch chain.

I claim the combinations:

1. In suspenders, a strap with an opening 55 therein; a hookloop having a loop and a hook; the loop adapted to be engaged by a suspender tab; the hook, consisting of a bar and a tongue, straddling the strap in the opening and therein freely swinging; an inserting, securing and retaining pin, for insertion in the opening, for securing the staying in of the hook in the opening, and adapted to retain a connecting strip, placed on the tongue, from slipping off, the pin projecting from the tongue at substantially a right angle to the plane in which the bar and tongue lie.

60 2. In suspenders, a shoulder piece with

openings; a hookloop having a stem; the stem at one end provided with a hook consisting of a bar and tongue straddling the shoulder piece in the openings, therein freely swinging and therein adapted to be step adjusted; an inserting and securing pin projecting from the tongue at a substantially right angle to the plane in which the bar and tongue lie and adapted to be passed through the openings; the stem at its other end provided with a loop for carrying a suspender tab.

3. In suspenders, a shoulder piece with 75 openings; a hookloop having a stem; the stem at one end provided with a hook consisting of a bar and tongue straddling the shoulder piece in the openings, therein freely swinging and therein adapted to be step adjusted; an inserting and securing pin projecting from the tongue at a substantially right angle to the plane in which the bar and tongue lie and adapted to be passed through the opening; the stem at its other end provided with a closed loop having a base from which at one end extends a branch connected with the stem, and at its other end extends a branch bent back and directed toward the connected branch to produce the closed loop; and a suspender tab carried by the loop.

4. In suspenders, a shoulder piece with 80 openings; a hookloop having a stem; the stem at one end provided with a hook consisting of a bar and tongue straddling the shoulder piece in the openings, therein freely swinging and therein adapted to be step adjusted; an inserting and securing pin projecting from the tongue at a substantially right angle to the plane in which the bar and tongue lie and adapted to be passed through the openings; the stem at its other end provided with a closed loop having a base from which at one end extends a branch connected with the stem, and at its other end extends a branch bent back and directed toward the connected branch to produce the closed loop; and a suspender tab carried by the loop.

5. In suspenders, a shoulder piece with 85 openings; a hookloop having a stem; the stem at one end provided with a hook consisting of a bar and tongue straddling the shoulder piece in the openings, therein freely swinging and therein adapted to be step adjusted; an inserting and securing pin projecting from the tongue at a substantially right angle to the plane in which the bar and tongue lie and adapted to be passed through the openings; the stem at its other end provided with an open loop having a base from which at one end extends a branch connected with the stem, and at its other end extends a free branch bent back and directed toward the connected branch, but sideways out of the plane in which the connected branch and the base lie; the free branch leaving an opening between it and the connected branch, for the passage of a one piece suspender tab, and for rendering the loop open.

toward the connected branch, but sideways out of the plane in which the connected branch and the base lie; the free branch going past the connected branch, here leaving 5 a passage, then bent around the connected branch to form a tip so as to continue the passage and to render the loop open for the passing of a one piece suspender tab.

6. In suspenders, two shoulder pieces; each 10 piece at the rear end having a buttonhole, and at the front end a row of openings and a hookloop provided at one end with a hook for step adjustingly engaging the openings; the hook furnished with an inserting, securing 15 and retaining pin designed to pass through the openings; the hookloop at the other end provided with a loop for carrying a suspender tab; a connecting strip which with step by step adjustment unites the two 20 hookloops, and thereby the shoulder pieces.

7. In suspenders, two shoulder pieces; each piece at the rear end having a buttonhole, and at the front end a row of openings and a hookloop provided at one end with a hook for step adjustingly engaging the openings, the hook furnished with an inserting, securing and retaining pin designed to pass through the openings; the hookloop at the other end provided with a loop for carrying 30 a suspender tab; a connecting strip which with step by step adjustment unites the two hooks, and thereby the shoulder pieces; a holding device on the connecting strip for holding a necktie in place.

35 8. In suspenders, two shoulder pieces; each piece at the rear end having a buttonhole, and at the front end a row of openings and a hookloop provided at one end with a hook for step adjustingly engaging the openings; the hook furnished with an inserting, securing and retaining pin designed to pass through 40 the openings; the hookloop at the other end provided with a loop for carrying a suspender tab; a connecting strip which with step by step adjustment unites the hook of one shoulder piece with the loop of the other piece, and thereby the shoulder pieces.

45 9. In suspenders, two shoulder pieces; each piece at the rear end having a buttonhole, and at the front end a row of openings and a hookloop provided at one end with a hook for step adjustingly engaging the openings; the hook furnished with an inserting, securing and retaining pin designed to pass through 50 the openings; the hookloop at the other end provided with a loop for carrying a suspender tab; a connecting strip which with step by step adjustment unites the two loops, and thereby the shoulder pieces; a holding device 55 on the connecting strip for holding a necktie in place.

60 10. In suspenders, two shoulder straps and two rear suspender tabs, constituting four parts only, to form two shoulder pieces, and 65 the tabs being of lesser width than the straps;

the straps at their rear ends crossing, and herefrom ascending at an angle for suitably passing over the shoulders; the rear suspender tabs at their upper ends also crossing and lying on the crossing of, and between, 70 the straps, and herefrom descending at an angle smaller than the angle of the shoulder straps, for suitably meeting and engaging garment buttons; means for uniting the two straps and the two tabs at the crossings for 75 forming a pad.

11. In suspenders, two shoulder straps of webbing; each strap from end to end having a continuous series of woven in slits; two rear suspender tabs of webbing, each from 80 end to end having a continuous row of woven in slits designed to serve as garment supporting buttonholes; the rear ends of the two straps united with the two rear tabs to form a pad; the hook of a hookloop in each strap 85 adapted to step adjustingly engage the slits at the front, each hook provided with an inserting, securing and retaining pin; the loop of each hookloop carrying a one piece front suspender tab of webbing having from 90 end to end a continuous series of woven in slits designed to serve as garment supporting button holes; a connecting strip of webbing having from end to end a continuous row of woven in slits, step adjustingly connecting 95 the two hookloops; and the strip carrying a safety pin for holding a necktie in position.
